CLAIM

The ornamental design for a pressure fit focus gear, as shown and described.

DESCRIPTION

FIG. 1 is a perspective view of a pressure fit focus gear showing my new design;

FIG. 2 is a front view, the rear view being a mirror image thereof;

FIG. 3 is a right side view, the left side view being a mirror image thereof; and,

FIG. 4 is a top view, the bottom view being a mirror image thereof.

1 Claim, 4 Drawing Sheets

FIG. 1

FIG. 2

FIG. 3
